TOY VEHICLE

Frank R. Labin, Buffalo, N. Y.

Application June 12, 1937, Serial No. 147,983

15 Claims.

(Cl. 46—213)

My invention relates in general to toy vehicles, and particularly to that type of vehicle which is propelled by means of a spring motor.

The principal object of my invention has been 5 to provide a toy vehicle or the like which is provided with mechanism for automatically steering the vehicle in a predetermined path of "figure 8" form of relatively small dimensions.

Another object has been to provide a wheeled 10 toy which is steered in its path of movement by means of the rear wheels.

Another object has been to provide a toy of 15 this nature which shall be inexpensive to manufacture and which shall be durable in construction.

The above objects and advantages have been accomplished by the device shown in the accompanying drawing, of which:

Fig. 1 is a sectional elevation taken through 20 the center of my complete device.

Fig. 2 is a plan view thereof with the top part removed.

Fig. 3 is a bottom, plan view.

Fig. 4 is an enlarged, fragmentary view of portions of the operating mechanism.

My device comprises a chassis part 10 having a base 9, made preferably of sheet metal and provided with an upturned edge 11 into which the body part 12 is designed to fit. The body part 25 may be secured to the chassis part by means of suitable tabs 13 carried by the body part and passed through slots 14 formed in the chassis part, such tabs being bent over or twisted after 30 passage through the slots.

The chassis comprises a pair of front wheels 15. The front wheels 15 are non-steering and are the driving wheels of my vehicle. These 35 wheels are mounted upon a driving shaft 16 which is preferably of hexagonal cross-section, and this shaft is pivotally mounted in bearing lugs 20 carried by the framework 21 of the driving motor 22, to be hereinafter described. The base 9 is provided at its forward end with a lateral slot 23 and two longitudinal slots 24, arranged one at each end of the lateral slot. These 40 slots provide space for the passage of the wheels 15 and the other driving parts of the mechanism which depend from the motor 22. At the outer edge of each of the slots 24 there is provided a reinforcing flange 25 which is bent down so as to stiffen the material around the slots.

The steering mechanism 26 of my device is arranged at the rear of the chassis of the vehicle and comprises two rear steering wheels 30 mounted upon a shaft 31 which is pivotally sup-

ported by a steering yoke 32 having two depending bearing flanges 33 arranged one at each end of the yoke. The yoke 32 is formed with an upwardly extending boss or fifth wheel 34. This fifth wheel is mounted in a recess provided 5 by an upwardly extending boss 35, formed in the base 9 and held therein by means of a rivet 36 which passes through the boss and through the fifth wheel 34.

The base 9 is provided with two oppositely 10 arranged arcuate slots 40 which have their radii struck from the center of the fifth wheel 34. Each of these slots has an upturned flange 41 extending around the entire periphery so as to reinforce the metal of the base. These arcuate 15 slots are wide enough to accommodate the rear wheels 30, the peripheries of which extend upwardly therethrough. The length of the slots is sufficient to permit the wheels to have unrestrained movement during the oscillatory path 20 of the yoke 32, as hereinafter described.

The base is also provided with an arcuate slot 42, struck also from the center of the fifth wheel, through which the downwardly extending portion 43 of an operating rod 44 is designed to pass. 25 This rod has its end extended through the arcuate slot 42 and is provided with an extreme lower, outwardly extending arm 47 which is engaged with a suitable aperture 45 formed in the fifth wheel. The forward end of the operating 30 rod is extended to and connected with the pin 46 of a crank 50 which forms a part of the spring shaft 51 of the motor. It will be seen that when the crank 50 is rotated, the operating rod 44 will be reciprocated back and forth and will cause 35 the fifth wheel 34, together with its yoke 32 and rear wheels 30, to be oscillated back and forth during the forward driving movement of the vehicle.

The motor 22 is located at the front of the 40 chassis and it is secured to the base 9 in any suitable way, but preferably by means of tabs 56 which may extend through slots 57 formed in the base. After the tabs are passed through the slots 57, they are bent over or twisted, as 45 desired. The spring shaft 51 is rotatably carried by the motor 22 in suitable manner and has the usual driving spring 52 attached to it, which spring is connected through suitable ratchet means, not shown. The motor is provided with 50 a driving gear 53 which is of the bevel type and is carried by an intermediate shaft 54. This driving gear is arranged preferably immediately above the base 9 and engages with a driving pinion 55 mounted upon the driving shaft 16. 55

The pinion 55 is preferably formed with a hexagonal opening whereby it may be conveniently mounted in non-rotating manner upon the driving shaft. The spring shaft 51 and the intermediate shaft 54, as well as the other parts, are suitably mounted in the framework 21 of the motor.

As hereinbefore stated, my invention is designed primarily to describe a path substantially 10 in the form of a "figure 8". In order to use such a toy it is quite essential, however, that the path described be relatively small. This, as hereinbefore stated, is accomplished in my invention by steering the vehicle by means of the rear wheels instead of the front wheels. It is when the motor 22 is wound up and the toy is placed upon the floor, the driving gear 53 will be rotated, which will cause the driving shaft 16, carrying the front wheels 15, to be rotated 20 through the medium of the pinion 55, thus propelling the vehicle in a forward direction. While the vehicle is being propelled, the spring shaft 51 is rotating, thereby causing the operating rod 44 to be reciprocated through the medium of the 25 crank 50 carried by the spring shaft. Since the rear end 43 of the operating shaft is engaged with the fifth wheel 34, this wheel will be oscillated back and forth so that each of the rear wheels 30 is alternately carried to the front and 30 to the rear of the vehicle in arcuate paths and substantially equidistantly from a transverse center line extending through the pivot of the fifth wheel 34. By so oscillating the rear wheels 30, the vehicle will be turned first to the left and 35 then to the right. The steering wheel is so geared in relation to the driving wheels that a relatively small "figure 8" will be described by the path of the vehicle.

When winding the vehicle, the driving wheels 40 15 may be held by the hand or suitable means, not shown, may be provided for locking the wheels either during winding or when it is desired to stop the vehicle.

Obviously, some modifications of the details 45 herein shown and described may be made without departing from the spirit of my invention or the scope of the appended claims, and I do not, therefore, wish to be limited to the exact embodiment herein shown and described, the form 50 shown being merely a preferred embodiment thereof.

Having thus described my invention, what I claim is:

1. A toy vehicle having a chassis, comprising a 55 base, a motor carried by the base, front wheels for the chassis, means connecting the motor with the front wheels for driving the vehicle, rear steering wheels for the chassis, said rear wheels being mounted upon a steering yoke, the yoke being formed with an upstanding boss, said base being formed with a recess for the reception of the boss, and means connecting the base with the yoke for causing an oscillatory movement of the yoke, whereby the vehicle is steered in substantially a "figure 8" path.

2. A toy vehicle having a chassis, comprising a 60 base, a motor carried by the base, front wheels for the chassis, means connecting the motor with the front wheels for driving the vehicle, rear steering wheels for the chassis, said rear wheels being mounted upon a steering yoke, and means connecting the yoke with the motor for causing an oscillatory movement of the yoke, said base being of such size as to extend over the wheels 70 at each side and end of the wheels and being

formed with arcuate slots for the reception of the steering wheels, whereby the vehicle is steered in substantially a "figure 8" path.

3. A toy vehicle having a chassis, comprising a 5 base, a motor mounted at the front end of the vehicle and secured to the base, driving wheels at the front of the vehicle and operatively connected with the motor, a pivoted steering yoke carried at the rear of the vehicle on the under side of the base, rear steering wheels pivotally carried by the said yoke, an operating rod arranged on the upper side of the base and having its forward end connected to the motor for giving to it a reciprocating movement, the base being formed with a slot to receive over the wheels at each side and end of the wheels and being formed with an arcuate slot, said operating rod having a rear end for passage through the slot of the base and for engagement with the yoke, whereby the rear 10 wheels will effect the steering of the vehicle.

4. A toy vehicle having a chassis, comprising a 15 base, a motor mounted at the front end of the vehicle and secured to the base, a crank actuated by the motor, driving wheels at the front of the vehicle and operatively connected with the 20 motor, a pivoted steering yoke carried at the rear of the vehicle on the under side of the base, rear steering wheels pivotally carried by the said yoke, an operating rod arranged on the upper side of the base, said rod having its forward end connected to the crank of the motor for giving to it a reciprocating movement, the base being formed with an arcuate slot, said operating rod having a rear end for passage through the slot of the base and for engagement with the yoke, whereby the rear 25 wheels will effect the steering of the vehicle.

5. A toy vehicle having a chassis, a pair of non-steering front wheels for the chassis, an axle for 30 said front wheels having a fixed axis, a motor for the chassis mounted upon and above the axle of the front wheels, a base secured to the motor, a body for the vehicle, carried by and secured to the base, the base being so positioned that substantially all of the motor and working parts of the device are enclosed and protected, a steering yoke pivotally carried at the rear end of the base, rear wheels pivotally carried by the yoke, the base being so proportioned that it extends beyond the wheels at the sides and ends of the vehicle, and operating means connecting the motor with the yoke for causing an oscillatory movement of the yoke, whereby the rear wheels 35 will effect the steering of the vehicle.

6. A toy vehicle having a chassis, a pair of 40 non-steering front wheels for the chassis, an axle for said front wheels having a fixed axis, a motor for the chassis mounted upon and above the axle of the front wheels, a base secured to the motor, a body for the vehicle, carried by and secured to the base, the base being so positioned that substantially all of the motor and working parts of the device are enclosed and protected, a steering yoke pivotally carried at the rear end of the base, rear wheels pivotally carried by the yoke, the base being so proportioned that it extends beyond the wheels at the sides and ends of the vehicle, said base being formed with slots for the passage therethrough of the upper portions of the front and rear wheels, and an operating 45 rod located on the top of the base and connecting the motor with the yoke for causing an oscillatory movement of the yoke, whereby the rear wheels will effect the steering of the vehicle.

7. A toy vehicle having a chassis, a pair of non- 50

steering front wheels for the chassis, an axle for said front wheels having a fixed axis, a motor for the chassis having a crank and mounted upon and above the axle of the front wheels, a base secured to the motor, a body for the vehicle, carried by and secured to the base, the base being so positioned that substantially all of the motor and working parts of the device are enclosed and protected, a steering yoke pivotally carried 10 at the rear end of the base, rear wheels pivotally carried by the yoke, the base being so proportioned that it extends beyond the wheels at the sides and ends of the vehicle, said base being formed with slots for the passage therethrough 15 of the upper portion of the front and rear wheels, and an operating rod located on the top of the base and connected at one end to the crank of the motor and at the other end to the steering yoke, whereby the rear wheels will be oscillated 20 and cause the vehicle to be steered in a substantially "figure 8" path.

8. A toy vehicle having a chassis, a pair of non-steering front wheels for the chassis, an axle for said front wheels having a fixed axis, a motor for the chassis having a crank and mounted upon and above the axle of the front wheels, a base secured to the motor, a body for the vehicle, carried by and secured to the base, the base being so positioned that substantially all of the motor and working parts of the device are enclosed and protected, a steering yoke pivotally carried 30 at the rear end of the base, rear wheels pivotally carried by the yoke, the base being so proportioned that it extends beyond the wheels at the sides and ends of the vehicle, said base being formed with slots for the passage therethrough of the upper portion of the front and rear wheels, and with an arcuate slot located 35 over the steering yoke, and an operating rod located on the top of the base and connected at one end to the crank of the motor and having its other end passed through the arcuate slot of the base and attached to the steering yoke, whereby the rear wheels will be oscillated and 40 cause the vehicle to be steered in a substantially "figure 8" path.

9. A toy vehicle having a chassis, front and rear wheels for the chassis, each pair of wheels being provided with an axle, a motor for the chassis mounted upon and above the axle of the front wheel, a base located between the motor and the axles and extending beyond the wheels at the sides and ends of the vehicle, said base being secured to the motor and being formed 50 with slots to permit the passage of the upper portions of the wheels therethrough, a steering yoke pivotally carried at the rear end of the base, the axle of the rear wheels being pivotally carried by the yoke, and operating means connecting the motor with the yoke for causing an oscillatory movement of the yoke, whereby the rear wheels will effect the steering of the vehicle.

10. A toy vehicle having a chassis, front and rear wheels for the chassis, each pair of wheels being provided with an axle, a motor for the chassis mounted upon and above the axle of the front wheel, a base located between the motor and the axles and extending beyond the wheels at the sides and ends of the vehicle, said base being secured to the motor and being formed 65 with slots to permit the passage of the upper portions of the wheels therethrough, a steering yoke pivotally carried at the rear end of the base, the axle of the rear wheels being pivotally carried by the yoke, the yoke being formed with an an-

nular, upstanding boss, said base being formed with a recess for the reception of the boss, and an operating rod connecting the motor with the yoke for causing an oscillatory movement of the yoke, whereby the rear wheels will effect the steering of the vehicle. 5

11. A toy vehicle having a chassis, front and rear wheels for the chassis, each pair of wheels being provided with an axle, a motor for the chassis mounted upon and above the axle of the front wheel, a base located between the motor and the axles and extending beyond the wheels at the sides and ends of the vehicle, said base being secured to the motor and being formed with slots to permit the passage of the upper 10 portions of the wheels therethrough, a steering yoke pivotally carried at the rear end of the base, the axle of the rear wheels being pivotally carried by the yoke, the yoke being formed with an annular, upstanding boss, said base being 15 formed with a recess for the reception of the boss, and an operating rod located on top of the base and connecting the motor with the yoke, for causing an oscillatory movement of the yoke, whereby the rear wheels will effect the steering 20 of the vehicle.

12. A toy vehicle having a chassis, front and rear wheels for the chassis, each pair of wheels being provided with an axle, a motor for the chassis mounted upon and above the axle of the front wheel, a base located between the motor and the axles and extending beyond the wheels at the sides and ends of the vehicle, said base being secured to the motor, the base being formed with slots on each side of the motor for the reception 30 of the upper portions of the front wheels, a steering yoke pivotally carried at one end of the base, the axle of the rear wheels being pivotally carried by the yoke, the base being formed with arcuate slots concentric with the pivot of 35 the yoke for the reception of the upper portions of the rear wheels, and an operating rod connecting the motor with the yoke for causing an oscillatory movement of the yoke, whereby the rear wheels will effect the steering of the vehicle. 45

13. A toy vehicle having a chassis, front and rear wheels will effect the steering of the vehicle, being provided with an axle, a motor for the chassis mounted upon and above the axle of the front wheel, a base located between the motor and the axles and extending beyond the wheels at the sides and ends of the vehicle, said base being secured to the motor and being formed with slots to permit the passage of the upper 50 portions of the wheels therethrough, a steering yoke pivotally carried at the rear end of the base, the axle of the rear wheels being pivotally carried by the yoke, the base being formed with an arcuate slot immediately over the steering 55 yoke, and an operating rod located on top 60 of the base and having one end connected to the motor for oscillation and the other end passing through the arcuate slot and connected to the yoke.

14. A toy vehicle having a chassis, front and rear wheels for the chassis, each pair of wheels being provided with an axle, a motor for the chassis having a crank and mounted upon and above the axle of the front wheel, a base located 65 between the motor and the axles and extending beyond the wheels at the sides and ends of the vehicle, said base being secured to the motor and being formed with slots to permit the passage of the upper portions of the wheels therethrough, a steering yoke pivotally carried at the 70 75

- rear end of the base, the axle of the rear wheels being pivotally carried by the yoke, the base being formed with an arcuate slot immediately over the steering yoke, and an operating rod located 5 on top of the base and having one end connected to the crank and its other end passed through the arcuate slot and connected to the yoke for causing an oscillatory movement of the yoke, whereby the rear wheels will effect the steering 10 of the vehicle.
15. A toy vehicle having a chassis, front and rear wheels for the chassis, each pair of wheels being provided with an axle, a motor for the chassis having a crank and mounted upon and above the axle of the front wheel, a base located between the motor and the axles and extending beyond the wheels at the sides and ends of the vehicle, said base being secured to the motor 15

and being formed with slots to permit the passage of the upper portions of the wheels therethrough, a steering yoke pivotally carried at the rear end of the base, the axle of the rear wheels being pivotally carried by the yoke, the yoke being formed with an annular, upstanding boss, said base being formed with a recess for the reception of the boss and with an arcuate slot formed through the metal in the recess, and an operating rod located in the top of the base 10 and having one end connected with the crank and the other end passing through the arcuate slot and secured to the upstanding boss of the yoke for causing an oscillatory movement thereof, whereby the rear wheels will effect the steering 15 of the vehicle.

FRANK R. LABIN.

CERTIFICATE OF CORRECTION.

Patent No. 2,152,064.

March 28, 1939.

FRANK R. LABIN.

It is hereby certified that error appears in the printed specification of the above numbered patent requiring correction as follows: Page 3, second column, line 4, claim 10, for the word "and" read an; line 47, claim 13, strike out the words and period "will effect the steering of the vehicle." and insert instead for the chassis, each pair of wheels; and that the said Letters Patent should be read with this correction therein that the same may conform to the record of the case in the Patent Office.

Signed and sealed this 27th day of June, A. D. 1939.

Henry Van Arsdale

Acting Commissioner of Patents.
